Philip T. Dodge

UNITED STATES PATENT OFFICE.

MOSES MARSHALL, OF CHICOPEE FALLS, MASS., ASSIGNOR TO THE LAMB
KNITTING MACHINE MANUFACTURING COMPANY, OF SAME PLACE.

KNITTING-MACHINE.

SPECIFICATION forming part of Letters Patent No. 267,982, dated November 21, 1882.

Application filed October 4, 1881. (No model.)

To all whom it may concern:

Be it known that I, MOSES MARSHALL, of Chicopee Falls, in the county of Hampden and State of Massachusetts, have invented certain 5 Improvements in Knitting-Machines, of which the following is a specification.

My invention relates more particularly to that class of knitters represented by the well-known Lamb machine, commonly known in 10 the art as "straight reciprocating" machines, wherein series of parallel needles mounted in grooved plates are moved endwise by means of cams attached to a reciprocating carrier-frame.

My invention relates especially to the cams 15 employed for operating the needles, said cams being commonly known in the art as "locks." These locks, of which there are two, located one 20 on each side of the machine, consist each of two cams for depressing the needles and an intermediate cam, or cams for elevating the needles.

The object of my invention is to adapt the 25 machine to produce a variety of fabrics by causing the cams to move the needles a greater or less distance, and to elevate or depress the needles to a different extent when moved in opposite directions.

To this end the invention consists in combining with the two depressing-cams an intermediate stationary depressing-cam of a Δ 30 form, having its lower ends exposed to serve as stops to limit the ascent of the needles; in the combination, with the foregoing, of the peculiarly-arranged elevating-cam having one end exposed and arranged to be lifted by the needles during the travel of the cams across the machine in one direction, and in various minor features and combinations, which will be hereinafter detailed; also, in combining with 35 said cam a locking device, by which it may be maintained permanently in its elevated position.

My invention is susceptible of embodiment in different forms without departing from the 40 limits of the invention or changing the mode of operation, the accompanying drawings, however, representing the device in the form in which I prefer to use it.

Referring to the drawings, Figure 1 repre-

sents a face elevation of my improved lock 50 with the parts adjusted and secured in position to elevate and depress the needles to their full limit. Fig. 2 is a similar view, showing the movable elevating-cam in its depressed position. Fig. 3 is a detailed view, illustrating 55 the manner in which the needles cause the elevating-cam to rise. Fig. 4 is an outside face view, illustrating the device for locking the elevating-cam upward. Fig. 5 is a cross-section on the line $x-x$, and Fig. 6 a cross-section on the line $y-y$, of Fig. 4. In Figs. 2 and 60 3 the arrows indicate the direction in which the locks are supposed to be moving when the parts are in the position represented.

A represents the lock-plate, to which the various cams are attached.

B B' represent the two V-shaped cams for depressing the needles, said cams being adjustably connected to the opposite ends of the plate A by means of screws a passing through 70 inclined slots b in the plate, as usual, the arrangement being such as to permit the cams B B' to slide upward and downward. As a means of adjusting and securing the cams B B', disks C are seated in the plate A, and are 75 provided with crank-pins d , engaging in horizontal slots e in the cams. The disks C will be provided on the outer side of the machine with finger-pieces or other ordinary means for operating and securing the disks, so that the attendant may readily adjust and secure the cams B B' at the desired elevations.

Between the cams B B', to the top of the lock-plate A, is secured rigidly a cam, D, of an inverted-V form, this cam bearing against and 85 maintaining at all times a close connection with the inner edges of the cams B B', and being recessed or cut away in its under side, as shown, so that the needle-shanks may rise within it. This cam D serves the purpose of 90 assisting the cams B B' in depressing the needles, and its lower horizontal ends, c , also serve to check the ascent of the needles, as herein-after described.

To the lower side of the lock-plate are secured rigidly two small elevating-cams, E and F, their outer edges being at such distance from the cams B B', respectively, as to permit the

needle-shanks, sometimes denominated "needle-butts," to pass between. The cams E and F are, as shown in the drawings, of limited height, and serve to elevate the needle-shanks 5 to a point immediately below the ends of the fixed depressing-cam D. Between the cams E and F is pivoted an elevating-cam, G, its pivot being located at one end and below its upper edge. This cam may be turned upward, 10 as shown in Fig. 3, above the level of the elevating-cams E and F, for the purpose of engaging the needle-shanks after they have reached the top of the cams E and F, and carrying them still higher in order to carry the 15 needles to the full limit of elevation, when required. The cam G is mounted loosely on its pivot, and when left free falls by gravity to the position represented in Fig. 2, with its end or nose projecting slightly above the upper 20 edge of the cam F, in such position as to be encountered by the needle-shanks riding upward over cam F. When the shanks of the ascending needles thus encounter the end of the cam G, they force the cam upward to the 25 position represented in Fig. 1, so that it causes all the needles to pass upward over it, thereby elevating them to their highest operative positions. The cam, being relieved from the pressure of the shanks of the needles, immediately 30 falls to its former position, in which it remains. During its movement in the opposite direction the needles pass upward over the cam E and backward over the cam G, without being further elevated thereby. It will 35 thus be seen that the effect of the cam G, when free, is to cause the needles to receive a much greater elevation as they are moved in one direction than when they are moved in the opposite direction.

40 As it is sometimes necessary to secure the cam G in its elevated position, in order that the needles may receive their full elevation during the movement of the cam in both directions, a hand-lever, H, is pivoted to the outer 45 side of the lock-plate and arranged, when moved in the direction of the arrow, to throw the cam upward and engage beneath the screw or stud thereon, as shown in Fig. 4; so as to lock the cam firmly in place.

50 The following are the various operations of my improved lock upon the needles when the machine is ready for operation:

When the cams G on both sides of the machine are locked in their elevated positions 55 the needles will rise in the needle-race to its highest point during the movement of the lock in each direction. As the lock moves in the direction indicated by the arrows in Fig. 3 the elevating-cam F first elevates the needles 60 to the lower end of the cam D, with which they come in contact. The needles now remain at rest until they are encountered by the advancing cam G, by which they are carried to their full elevation, after which they are depressed by the cam D until they reach its lower 65 end, after which they are acted upon by the cam B and carried to their lowest limit. In

this manner the needles are given their full length of movement during the passage of the lock in both directions. When the cam G is unlocked and left free the operation is as follows: As the lock moves in the direction indicated by the arrows in Fig. 2 the needles are partially elevated by the fixed cam E, and, after remaining momentarily at rest, are depressed by the action of the advancing cam B'; but during the movement of the lock in the opposite direction, as indicated by the arrows in Fig. 3, the needles are partially elevated by the cam F, and after encountering the lower end of the cam B they are encountered by the advancing cam G. The needles, acting against the free end of the cam G, cause the same to rise to its uppermost position, (represented in Fig. 1,) the cam thus elevated passing beneath 85 the needles and compelling them to rise to their highest elevation. After the passage of the upper point of the cam beneath them the needles are acted upon by the cam D and partially depressed, after which they are acted upon by the cam B and carried to their lowest limit of movement.

It will be observed that under the last-named arrangement the needles receive a full elevation and depression while the lock is 95 passing in one direction, but a partial elevation only when the lock is moved in an opposite direction. The result of this action is that as the lock passes in one direction the needles each retain the previous stitch instead of casting it over the latch, at the same time taking yarn for another stitch, so that when they have completed their motion the previous stitch and the yarn for another stitch are both on the needle; but during the reverse motion 105 of the machine the needle casts both the old and the new stitches, and forms a single new stitch during the return motion, and thus produces a fabric of the Royal rib or half Cardigan pattern.

In making the full Cardigan fabric the cams G on both sides of the machine are unlocked, and as the two cams have their free ends directed toward opposite ends of the machine they are elevated alternately, one being operated as the locks move in one direction and the other elevated as the locks move in the opposite direction. The result of this arrangement is that as the needle-carrying frame moves in one direction one set of needles will be elevated to their highest point and caused to cast their stitches, while the other set will rise only to the middle point and retain their stitches, and vice versa. By this operation the stitches are cast alternately on the two sides of the machine, producing the full Cardigan stitch.

The Derby rib fabric is made when both the cams G are locked upward and the needles receive their full movement, the half Cardigan or Royal rib when one of the cams G is locked up and the other left free, and the full Cardigan when both of the cams G are unlocked.

One of the great advantages of the automatic cam G is that in the forward or backward

motion of the cam it always assumes its proper position without difficulty and without clogging the machine, so that the cams may be passed over any given number of needles required and 5 reversed as readily at one point as at another.

Having thus described my invention, what I claim is—

1. The combination of the needles, two depressing-cams, B B', and an intermediate cam, 10 D, of a A form, having its lower ends constructed and arranged to limit the ascent of the needles in the passage of the cams across the machine in both directions at such point as to prevent them from casting the previously- 15 formed stitches, substantially as described and shown.

2. The two depressing-cams B B' and means for adjusting them in the manner described, in combination with the depressing-cam D, having the exposed ends C, as described and shown. 20

3. The combination of the fixed depressing-cam, recessed in its lower side to admit the needle-shanks, and two adjustable depressing-cams, seated against and forming a downward 25

continuation of the opposite sides of the fixed cam, as described and shown.

4. The combination of the depressing-cams B, B', and D and the elevating-cams E, F, and G, constructed and arranged for joint operation substantially as shown. 30

5. In combination with the depressing-cams, the intermediate elevating-cam, G, pivoted at one end and arranged to be elevated by the action of the needle-shanks against its opposite end, and means, substantially as described, 35 whereby said cam may be fixed rigidly in position at will.

6. The combination of the stationary elevating-cams E and F, the intermediate pivoted cam, G, constructed in the manner described 40 and shown, and the pivoted latch or support H to sustain the pivoted cam, as described and shown.

MOSES MARSHALL.
